CLAIM

The ornamental design for a control element with surface ornamentation for an electrical device, as shown and described.

DESCRIPTION

The patent or application file contains at least one drawing executed in color. Copies of this patent with color drawings will be provided by the Office upon request and payment of the necessary fee.

The sole FIGURE is a plan view of the control element with surface ornamentation for an electrical device showing our new design. The sides and back of the design do not form a part of the claimed design. The control elements are shown on the surface of an electrical device wherein the depth of the surface is not being claimed. The shade of gray of the surface shown is an integral part of the claimed design.
